(57) **CLAIM**

The ornamental design for a skimmer lid thermometer, as shown and described.

DESCRIPTION

FIG. 1 is a top perspective view of a skimmer lid thermometer, showing our new design;

FIG. 2 is a bottom perspective view thereof;

FIG. 3 is a top plan view thereof;

FIG. 4 is a bottom plan view thereof; and,

FIG. 5 is a front elevation view thereof.

The broken lines in the figures illustrate portions of the skimmer lid thermometer that form no part of the claimed design.
